UNITED STATES PATENT OFFICE.

URIAS T. HIGHT, OF CANDOR, NORTH CAROLINA.

PEA-HULLER.

1,107,424.

Specification of Letters Patent. Patented Aug. 18, 1914.

Application filed August 30, 1912. Serial No. 717,880.

To all whom it may concern:

Be it known that I, URIAS T. HIGHT, a citizen of the United States, residing at Candor, in the county of Montgomery, State of North Carolina, have invented certain new and useful Improvements in Pea-Hullers; and I do hereby declare the following to be a full, clear, and exact description of the invention, such as will enable others skilled in the art to which it appertains to make and use the same.

This invention relates to improvements in pea hullers and threshers and particularly to a rethreshing device.

The principal object of the invention is to provide an improved construction and arrangement of the parts whereby the peas are better threshed than in devices heretofore.

Other objects and advantages will be apparent from the following description and with particular reference to the accompanying drawings.

In the drawings: Figure 1 is a side elevation of a threshing machine made in accordance with my invention, Fig. 2 is a top plan view thereof, Fig. 3 is an end elevation taken from the cylinder end of the machine, Fig. 4 is an end elevation taken from the opposite side, Fig. 5 is a central vertical longitudinal sectional view through the machine, Fig. 6 is a vertical transverse sectional view on the line 6—6 of Fig. 5.

Referring particularly to the accompanying drawings, 10 represents a housing, in one end of which is mounted a toothed cylinder 11 and a toothed concave 12. On top of the housing 10 is a hopper 13 into which the peas are held and which are fed from the end of the board 14 to the cylinder and to the concave. Within the housing, and just below the cylinder 11 is an upwardly inclined guard 15 over which the peas, which have passed between the cylinder and concave, travel, and are deposited on the upwardly and rearwardly inclined screen 16 over which is mounted the conveyer belt 17. The rear end of the screen 16 terminates a short distance from the housing 10, the upper portion of said rear end of the housing 50 being open as indicated at 18. The mesh of this screen is of such size that the peas will fall therethrough at some point in their upward travel. In the lower part of the rear of the housing 10 is another inclined guard member 19, but slightly greater in size than the guard 15, the upper end of the guard 19

being disposed a short distance from the rear end of the screen 16. The peas which have been carried by the conveyer belt 17 drop off the rear end of the screen 16 onto the inclined guard 19, which guard directs them into the chute or spout 20 arranged at the rear of the housing. The bottom of the said chute or spout 20 is downwardly and transversely inclined which directs the peas to the lower end of the inclined conveyer 21, the upper end of which terminates over the chute 14 so that the peas which pass into this conveyer are redeposited between the cylinder and concave, thus providing that they be rethreshed.

A transverse shaft 23 extends through the housing, and has on its ends the belt wheels 24 and 25, which drive the cylinder by means of the belt 26, a smaller belt wheel 27 being arranged on the same shaft and on the same side of the machine and communicating motion to the conveyer 21 by means of the belt 28, the belt wheel 25 being on the same shaft and of the same diameter but on opposite side of the machine and on the same side as the conveyer 21. In the forward end of the housing is a fan casing 30, in which is mounted a blast fan 31. At the rear of the fan casing 30 is formed the nozzle 32 which directs the blast of air against the forward inclined surface 33' of the guard 19 so that said air will pass up between the said guard and screen 16. As the unhulled ends of the peas and chaff drop from the rear end of the screen 16, the blast of air will blow the chaff through the opening 18 while the peas, being heavier than the chaff, will drop on to the guard 19 and be conveyed back to the cylinder. The peas which drop through the screen 16, fall through the spout 32, into a receptacle placed thereunder, this spout being arranged in the bottom of the housing at the lower end of the guard 33'. By this arrangement the blast of air is directed upwardly and rearwardly and positively insures that the chaff will be blown from the housing, and danger of the same entering again with the material being threshed is reduced to a minimum.

The conveyer belt 17 consists of two bands 33, arranged parallel to each other and passing over the rollers 34. Extending across from one belt to the other, and secured thereto, are the regularly spaced strips 35, each of which carries a series of

outwardly extending rake teeth or pins 36. These rakes engage and carry the peas, that have passed between the cylinder and concave, up the inclined screen 16.

5 In the side of the fan casing is formed an opening 37, and pivotally mounted on the casing, and adapted to be moved over the opening to regulate the amount of air which passes into the fan casing is a gate 10 38. On the pivot bolt of the gate is a thumb screw by means of which the gate may be held in any position.

On said transverse shaft 23 is a toothed sprocket 39, and an endless chain belt 40 15 for communicating motion to the conveyer 17. The transverse shaft 40' extending through the cylinder has on one end a small belt wheel 41 for driving the fan 31, by means of the belt 42, said belt wheel 41 being 20 on the opposite side of the housing from the belt 26.

What is claimed is:

In a pea huller and thresher, the combination with a hulling mechanism including a housing, an upwardly and rearwardly inclining conveyer within the housing, a screen below the conveyer, said screen terminating adjacent the rear end of the housing, the rear end of the

housing having an opening adjacent the end 30 of the said screen, of a downwardly and outwardly inclined guard wall extending from a point forwardly of and below the rear end of the said screen to the lower side of said opening, a guard wall downwardly 35 and forwardly inclined from the inner end of the last mentioned guard wall, the said walls at their point of connection being spaced from the screen inwardly of the said end of the screen, and a blast fan having a nozzle disposed to direct the blast of air against the lower portion of the downwardly and forwardly inclined guard wall, the discharge end of the conveyer being so disposed with relation to the last mentioned 45 guard wall that said conveyer will discharge the partially threshed material beyond the upper ends of the guard walls and across the current of air which issues from the upper end of the space between the screen 50 and the downwardly and forwardly inclined wall.

In testimony whereof, I affix my signature, in presence of two witnesses.

URIAS T. HIGHT.
